UNITED STATES PATENT OFFICE.

MIKE JAKAB, OF WOODLAND, MAINE.

AUTOMATIC STUFF-BOX FOR PAPER-MAKING MACHINES.

1,251,381.

Specification of Letters Patent. Patented Dec. 25, 1917.

Application filed August 13, 1917. Serial No. 185,899.

To all whom it may concern:

Be it known that I, MIKE JAKAB, a subject of the King of Hungary, residing at Woodland, in the county of Washington and State 5 of Maine, have invented certain new and useful Improvements in Automatic Stuff-Boxes for Paper-Making Machines, of which the following is a specification.

The primary object of my invention is the 10 provision of an automatically controlled device for stuff boxes whereby a uniform flow of stock is provided without requiring the attention of an attendant, the device being easy to manufacture and install and calculated to save expense in operating the plant.

A further object of the invention is the provision of a stuff box structure for paper making machines for automatically providing a return to the chest of all surplus stock 20 and thereby relieving any excess pressure at the outlet from the stuff box to the mixing box.

With these general objects in view and others that will appear as the nature of the 25 invention is better understood, the same consists in the novel construction, combination and arrangement of parts hereinafter more fully described, illustrated in the accompanying drawings, and pointed out in the 30 appended claims.

In the drawings forming a part of this application, and in which like designating characters refer to corresponding parts throughout the several views,

35 Figure 1 is a central vertical longitudinal sectional view through the device in its normal arrangement,

Fig. 2 is a front elevation of the device,

40 Fig. 3 is a transverse vertical sectional view taken upon line III—III of Fig. 1,

Fig. 4 is a top plan view of the device,

Fig. 5 is a sectional view similar to Fig. 1 with the device in its operating arrangement,

45 Fig. 6 is a vertical transverse sectional view taken upon line VI—VI of Fig. 5,

Fig. 7 is a perspective view of the controlling slide and

50 Fig. 8 is a perspective view of one of the partitions.

Referring more in detail to the drawings, a stuff box 10 is arranged which is adapted to communicate with the usual mixing box, not shown, for the stock by means of a spout

55 11 arranged adjacent an outlet 12 in the front wall or end 13 of the stuff box. A

partition 14 is arranged within the box 10 extending upwardly from the bottom to about one-half of the height of the box while the outlet 12 is controlled by a valve 15 pivoted to the forward end of a rocking bar 16 pivoted to a yoke 17 spanning and mounted upon the stuff box 10. The valve 15 is guided by means of a plate 18 secured to the inner side of the front wall 13 while a sliding weight 19 is arranged upon a notched reduced rear end portion 20 of the rocking lever 16 for assisting in adjustably maintaining the valve 15 in its operative position.

A partition 21 is arranged transversely 70 within the stuff box 10 rearwardly of the partition 14 and terminating only slightly spaced beneath the upper edges 22 of the longitudinal side walls 23 of the stuff box and is arranged with a central beveled top 75 portion 24. A doorway is provided in the bottom of the partition 21 normally covered by means of a slide 26 and adapted to be retracted when desired by means of a headed rod 27 projecting laterally of the box 10. 80

A controlling slide 28 is vertically shiftably arranged within the box 10 in flat contact with the rear partition 21 and is provided with an opening 29 registering with the beveled portion 24 of the partition 21, a 85 bail 30 being attached to the slide 28 and pivoted as at 31 to the rocking lever 16. A forward hinged cover member 32 and a rearward hinged cover member 33 is provided for the box 10 having their inner edges substantially in contact with each other when the covers are closed. The forward cover 32 rests upon the beveled upper edge 34 of the slide 28 while a channel plate 35 is swingingly mounted within the opening 29 90 of the slide 28 upon a rod 36 which passes through the bail 30 and through guide slots 37 in the sides 23 of the box 10.

The locking plate 35 is adapted to swing upwardly over the adjacent edge of the 100 cover 32 while a resilient latch 38 is carried by the cover 32 for springing over the plate 35 and retaining the same in position but permitting the rocking movement at the point of contact between the slide 28 and the 105 cover 32 when the slide is raised and lowered. A slightly curved plate 39 is carried by the forward edge of the cover 33 for overlying the latch 38 and the adjacent portion of the cover 32.

110 The stock is pumped into the stuff box 10 through the inlet pipe 40 into the space be-

tween the partitions 14 and 21 and when sufficient stock has been pumped into the box to reach the top of the partition 14, the stock flows over the top of said partition 14 to the 5 outlet 12 and beneath the valve 15 to and through the spout 11. The weight 19 is set for permitting the desired flow of stock through the outlet 12 while in the event of pumping of an excess of stock into the box 10, the stock will engage the cover 32 of the box thereby elevating the cover as well as the slide 28 and bail 30 for tilting the lever 16 partially closing the valve 15 and maintaining the flow of stock constant through 15 the outlet 12 regardless of the increased pressure upon the stock. This elevating of the slide 28 permits the surplus stock to flow over the top of the rear partition 21 into the space between the said partition and the rear 20 wall or end 41 of the box 10 for returning by means of the outlet pipe 42 in the bottom of the box to the stock chest 43 suitably arranged beneath the level thereof. The slide 26 may be manually opened by means of the 25 rod 27 when it becomes necessary to further relieve the pressure upon the stock within the box 10. Opposite guide strips 44 are provided for the slide 28 and it will be seen that with the covers 32 and 33 in their normal closed positions, the stock may readily 30 elevate the cover 32 carrying the cover 33 therewith as well as the slide 28 permitting the return of the stock through the slide opening 29. In this manner, the flow of 35 stock through the outlet 12 will be maintained normal automatically during the operation of the machine and the continuous pumping of the stock into the box 10 through the inlet pipe 40 from the stock 40 chest 42.

What I claim as new is:—

1. An automatic controlling means for the stuff box of a paper making machine, comprising in combination with a stuff box having 45 an outlet in its forward wall, a controlling valve for said outlet, partitions within the box forming receiving and discharging compartments therein, an inlet for stock into one of said compartments and an outlet from the 50 adjacent compartment, a controlling slide between the said compartments, associated hinged lids for the box operatively connected to the said slide adapted for opening simultaneously with the opening of the said lids, 55 and operating connections between the said valve and slide.

2. In combination with a stuff box having an outlet for stock, a controlling valve for said outlet, an adjusting lever for said valve, 60 a partition within the box terminating adjacent the top thereof, inlet and overflow pipes for the said stock arranged on opposite sides of the partition, a slide adapted for controlling the passage of surplus stock over the 65 said partition, a supporting bail connected

between the said slide and lever, and a hinged cover for the box overlying and attached to the slide whereby the elevating of the cover is adapted for opening the slide.

3. In combination with a stuff box having 70 an outlet for stock, a controlling valve for said outlet, an adjusting lever for said valve, a partition within the box terminating adjacent the top thereof, inlet and overflow pipes for the said stock arranged on opposite sides of the partition, a slide adapted for controlling the passage of surplus stock over the said partition, a supporting bail connected between the said slide and lever, a hinged cover for the box overlying and attached to the slide whereby the elevating of the cover is adapted for opening the slide, a freely swinging rear cover for the box resting upon the first-mentioned cover, a balancing weight adjustably mounted upon 80 the free end portion of the lever, and a manually controlled opening slide carried by the 85 said partition.

4. A stuff box for paper making machines having an outlet in one end, relatively low 90 and high partitions arranged within the box, an inlet for stock communicating with the interior of the box between the said partitions, a return pipe for excess stock leading from the box rearwardly of the higher partition and of the opposite end of the box from the said outlet, a vertically movable slide having an opening therethrough and operatively arranged adjacent the said higher partition adapted for controlling the passing 95 of surplus stock rearwardly thereover, a vertically movable valve for the said outlet opening, a rocking lever for the said valve, and automatic controlling means for the slide associated with the said lever. 100

5. A stuff box for paper making machines having an outlet in one end, relatively low and high partitions arranged within the box, an inlet for stock communicating with the interior of the box between the said partitions, a return pipe for excess stock leading from the box rearwardly of the higher partition and of the opposite end of the box from the said outlet, a vertically movable slide having an opening therethrough and operatively arranged adjacent the said higher partition adapted for controlling the passing 110 of surplus stock rearwardly thereover, a vertically movable valve for the said outlet opening, a rocking lever for the said valve, a bail connection between the said slide and lever, a hinged cover for said box resting upon the said slide within the said bail, a swinging channel plate carried by the slide normally overlying the adjacent edge 115 of the cover, and a retaining latch upon the said cover adapted for resilient seating over the said plate. 125

6. A stuff box for paper making machines having an outlet in one end, relatively low 130

and high partitions arranged within the box, an inlet for stock communicating with the interior of the box between the said partitions, a return pipe for excess stock leading 5 from the box rearwardly of the higher partition and of the opposite end of the box from the said outlet, a vertically movable slide having an opening therethrough and operatively arranged adjacent the said 10 higher partition adapted for controlling the passing of surplus stock rearwardly thereover, a vertically movable valve for the said outlet opening, a rocking lever for the said valve, a bail connection between the said 15 slide and lever, a hinged cover for said box

resting upon the said slide within the said bail, a swinging channel plate carried by the slide normally overlying the adjacent edge of the cover, a retaining latch upon said cover adapted for resilient seating over the 20 said plate, a rear cover hinged to the box, a cover plate carried by said rear cover adapted for overlying the adjacent edge portion of the first-named cover and latch, an adjusting weight upon the said lever, and a 25 manually operable opening slide for the said higher partition.

In testimony whereof I affix my signature.

MIKE JAKAB.
